UNITED STATES PATENT OFFICE.

MAX KECK, OF CRESCENT SPRINGS, KENTUCKY.

MACHINE FOR ROLLING METAL.

Application filed March 26, 1921. Serial No. 455,828.

To all whom it may concern:

Be it known that I, MAX KECK, a citizen of the United States of America, and a resident of Crescent Springs, in the county of 5 Kenton and State of Kentucky, have invented a new and useful Improvement in a Machine for Rolling Metal, of which the following is a specification.

An object of my invention is to provide a 10 mill to roll metals such as gold, etc., into very fine sheets, in which the axis of the shafts will be parallel at all times and in which there will be no lost motion between the driving means and the rolls.

15 Another object is to provide a device for the purposes stated that is capable of very fine adjustment.

Another object is to provide a device for the purposes stated that will roll the metal 20 into smooth sheets devoid of waves, ridges, or humps.

Another object is to provide a device of the type referred to that is simple in construction and operation.

25 These and other objects are attained by the means described herein and disclosed in the accompanying drawing in which:

Fig. 1 is a side elevation of a device embodying my invention, parts being broken 30 away.

Fig. 2 is a sectional view on line 2—2 of Fig. 1.

Fig. 3 is a sectional view on line 3—3 of Fig. 1.

35 My invention comprises a frame or housing A upon which are mounted the adjustable bearing blocks b and b' supporting the rolls D and D' adapted to be revolubly actuated and between which the metal to be rolled is passed. The rolls are adapted to be 40 adjusted in relation to one another by means of a hand lever g and a cam F acting upon the bearing blocks b and b'.

The housing or frame A has a base a¹¹ 45 from which extend the slotted uprights or sides a and a'. The slots a² in the sides are preferably vertical and are parallel with one another. The top a¹² connects the upper ends of the sides a and a'. The housing has 50 a way a³ extending therethru from the front a⁴ to the rear a⁵. The slots a² register with the way a³. A transverse bore a⁶ is formed in the top or head a¹² of the housing, and within this bore is rotatively mounted a 55 crank shaft a⁷. A hand crank a⁸ is mounted on the crank shaft a⁷. A bevel gear a⁹ is

mounted on the shaft a⁷. A transverse bore a¹⁰ is formed in the base and communicates with the lower ends of the slots a² in the sides. The bore also communicates with the way a³.

Slidably mounted in the slots a² in the sides of the housing are the upper bearing blocks b and the lower bearing blocks b' between which are disposed the springs b². 65 The upper blocks b are retained at the upper end of the slots a² by the action of the springs b².

The upper revoluble shaft c is mounted upon the upper blocks b, and the lower revoluble shaft c' is mounted in the lower blocks b'. An upper roller D and a lower roller D' are mounted upon the shafts c and c' respectively and are disposed in the way a⁸ intermediate the sides a and a' of the frame A. The shafts c and c' extend thru the bearing blocks b and b' in the slot in the side a' of the frame. The worm wheels d and d' are mounted upon the shafts c and c' respectively and engage the worms e' and e² 80 respectively mounted on the shaft e supported upon the exterior of the side a' by any suitable means such as the brackets e³. The drive shaft e has mounted upon its upper end a bevel gear e⁴ engaging the bevel gear a⁹. The worms e' and e² are right and left hand worms adapted when revolved, to actuate the worm wheels in opposite directions. A cam shaft F is rotatably mounted 85 in the transverse bore a¹⁰ and has formed on it the cams f and f' which lie in the bore a¹⁰ immediately below the slot a². On each cam is formed a cam face f² adapted to be moved past the slots a² and to engage the lower ends of the lower blocks b². A downwardly projecting lug f³ extends from the cam F. A threaded hand crank g is adjustably mounted in a threaded way a¹³ formed on the forward wall of the base a¹¹ of the housing A and engages the lug f³ on the cam. 90

The shafts c and c' are mounted on the frame in parallelism.

The operation of my device is as follows: 105 Rotatory motion is transmitted to the rollers D and D' by means of the crank a⁸, crank shaft a⁷, bevel gears a⁹, and e⁴, drive shaft e, worms e' and e², worm wheels d and d' and the shafts c and c'. Because the worms are right and left hand, the rollers 110 will be actuated in opposite directions where by the rolls will feed a strip of metal be-

tween themselves as they roll the metal. The rollers are adjustable in relation to one another by means of the hand crank g . When the hand crank is actuated so as to revolve the cam F , as shown in Fig. 1, in a counter-clock-wise direction, the cam faces f^2 move the lower blocks b' upward into the slots a^2 and against the springs b^2 , thereby bringing the rollers into closer relation. When the cam F is actuated in a clock-wise direction, the springs b^2 retain the blocks b' upon the cam face f and the blocks separate wherefor the rollers are moved apart. The worms and worm wheels permit ready adjustment of the rolls without the development of lost motion between the rolls, wherefor the metal will be rolled into uniform sheets devoid of waves or ridges.

If desired the springs b^2 may be dispensed with and the blocks b be fixedly retained upon the frame at the upper end of the slots a^2 . A spring a^{14} is then mounted upon the base of the frame and on the cam F . The spring yieldingly retains the lug f^3 in engagement with the crank g . When the crank g is moved out of the threaded way a^{13} , the cam faces f^2 are moved away from the slots a^2 , and the weight of the lower roll together with the shaft and blocks supporting the roll, cause the lower roll to separate from the upper fixed roll.

What I claim is:—

1. In a device of the class described the combination of a base having a transverse bore, slotted sides mounted on the base, the slots therein registering with the transverse bore, blocks mounted slidably in the slots, cooperating rolls mounted upon the blocks and disposed intermediate the sides, means yieldably spacing the blocks, a cam shaft revolvably mounted in the transverse bore, cams on the cam shaft engaging the blocks and adapted to adjustably move the blocks against the yieldable spacing means, and means to impart rotatory motion to the rolls.

2. In a device of the class described the combination of a housing comprising a base, a top, and slotted sides and having a transverse bore communicating with one of the ends of each of the slots in the sides, a drive shaft mounted on the housing parallel with the slots, a right hand and left hand worm mounted on the drive shaft, blocks mounted slidably in the slots in the sides, cooperating rolls mounted upon the blocks, worm wheels adapted to transmit motion to the rolls and engaging the worms, means yieldably spacing the blocks, and rotatable cams disposed within the transverse bore adapted to adjustably position the blocks in the slots.

3. In a device of the class described the combination of a housing comprising a base, a top, and slotted sides, and having a

transverse bore communicating with the lower ends of the slots in the sides, an upper bearing block and a lower bearing block mounted slidably in each of the slots, springs yieldingly spacing the upper and lower blocks, a roll shaft mounted revolvably upon the upper blocks, a roll shaft mounted revolvably upon the lower blocks, rolls mounted on the roll shafts adapted to jointly operate on material passed therebetween, a worm wheel mounted on each roll shaft, a drive shaft mounted on the housing, right and left hand worms mounted on the drive shaft and each engaging one of the worm wheels, a crank adapted to rotate the drive shaft, and a cam mounted in the transverse bore adjustably engaging the lower blocks.

4. In a device of the class described the combination of a housing comprising a base, a top, and slotted sides, and having a transverse bore communicating with the lower ends of the slots in the sides, an upper bearing block and a lower bearing block mounted slidably in each of the slots, springs yieldingly spacing the upper and lower blocks, a roll shaft mounted revolvably upon the upper blocks, a roll shaft mounted revolvably upon the lower blocks, rolls mounted on the roll shafts adapted to jointly operate on material passed therebetween, a worm wheel mounted on each roll shaft, a drive shaft mounted on the housing, right and left hand worms mounted on the drive shaft and each engaging one of the worm wheels, a crank adapted to rotate the drive shaft, a cam mounted in the transverse bore adjustably engaging the lower blocks, and means to revolvably actuate the cam in the bore to adjust the rolls.

5. In a device of the class described the combination of a base having a transverse bore, sides having vertical slots therein registering with the transverse bore, a head connecting the upper ends of the sides and having a transverse bore therein, a crank shaft mounted revolvably in the transverse bore in the head, a vertical shaft mounted on one of the sides, a bevel gear on the crank shaft engaging a bevel gear on the drive shaft, right and left hand worms mounted on the drive shaft, upper and lower bearing blocks mounted slidably in the slots in the sides, springs yieldably spacing the upper and lower bearing blocks, an upper roll shaft mounted upon the upper bearing blocks, a lower roll shaft mounted on the lower bearing blocks, worm wheels mounted on the roll shafts engaging the worms, cooperating rolls mounted on the roll shafts intermediate the sides, a cam shaft mounted revolvably in the transverse bore in the base, cam faces formed on the cam shaft adapted to engage the lower bearing blocks, and means

to revolubly actuate the cam shaft whereby the lower bearing blocks are adjustably actuated in the slots in the sides.

6. In a device of the class described the combination of a base having a transverse bore, sides having vertical slots therein registering with the transverse bore, a head connecting the upper ends of the sides and having a transverse bore therein, a crank shaft mounted revolubly in the transverse bore in the head, a vertical drive shaft mounted on one of the sides, a bevel gear on the crank shaft engaging a bevel gear on the drive shaft, right and left hand worms mounted on the drive shaft, upper and lower bearing blocks mounted slidably in the slots in the sides, springs yieldably spacing the upper and lower bearing blocks, an upper roll shaft mounted upon the upper bearing blocks, a lower roll shaft mounted

on the lower bearing blocks, worm wheels mounted on the roll shafts engaging the worms, cooperating rolls mounted on the roll shafts intermediate the sides, a cam shaft mounted revolubly in the transverse bore in the base, cam faces formed on the cam shaft adapted to engage the lower bearing blocks, a lug formed on the cam shaft, and a crank adjustably mounted on the base adapted to engage the lug on the cam shaft whereby the cam shaft may be revolubly actuated so as to move the cam faces over the lower bearing blocks and the bearing blocks are adjustably reciprocated in the slots in the sides.

In testimony whereof, I have hereunto subscribed my name this 23rd day of March, 1921.

MAX KECK.
